Primary Examiner — Keli L Hill

(57) **CLAIM**

The ornamental design for a portable digital-to-analog converter as shown and described.

DESCRIPTION

1.1: Perspective

1.2: Perspective

1.3: Front

1.4: Back

1.5: Left

1.6: Right

1.7: Top

1.8: Bottom

The claimed design is for a partial design and portions thereof which are represented with broken lines form no part of the claimed design. FIG. 1.1 is a front, right side, top perspective view of a portable digital-to-analog converter showing a new design; FIG. 1.2 is a front, right side, bottom perspective view thereof; FIG. 1.3 is a front view thereof; FIG. 1.4 is a rear view thereof; FIG. 1.5 is a left side view thereof; FIG. 1.6 is a right side view thereof; FIG. 1.7 is a top view thereof; and FIG. 1.8 is a bottom view thereof.

1 Claim, 8 Drawing Sheets
